UNITED STATES PATENT OFFICE.

PAUL M. MARKO, OF BROOKLYN, NEW YORK.

STORAGE-BATTERY-CELL COVER.

Application filed April 12, 1921. Serial No. 460,717.

To all whom it may concern:

Be it known that I, PAUL M. MARKO, a citizen of the United States, and a resident of the city of New York, borough of Brooklyn, in the county of Kings and State of New York, have invented a new and Improved Storage-Battery-Cell Cover, of which the following is a full, clear, and exact description.

10 This invention relates to storage battery cells, and has particular reference to covers for such devices.

Among the objects of the invention is to provide improved facilities for locking the 15 plates and cover together; to provide improved splash cover and electrolyte gage; and, finally, to generally improve the construction of the cell cover both for individual cell purposes and the assembly of a plurality of cells in the construction of a battery.

With the foregoing and other objects in view, the invention consists in the arrangement and combination of parts hereinafter described and claimed, and while the invention is not restricted to the exact details of construction disclosed or suggested herein, still, for the purpose of illustrating a practical embodiment thereof reference is had to 25 the accompanying drawings, in which like reference characters designate the same parts in the several views, and in which—

Figure 1 is a vertical central section of a cell and its cover complete; and

35 Figure 2 is a plan view of the splash cover.

Referring now more specifically to the drawings, I show a cell cup 10 made of any suitable non-corrodible material, the same being as usual of any suitable size or proportions and of rectangular form. The positive and negative posts 11 and 12 of the plates 13 and 14 extend upward as usual above the top of the cell cup and the several plates arranged in alternation are separated by wood or other fibrous plates 15. The terminals or binding posts 11 and 12 are provided at their shoulder portions 16 where they are connected to the several metal plates with horizontal kerfs 17 on the same level, such level being just above the desired level of the electrolyte indicated at 18. These kerfs are formed on the inner or opposed sides of the binding posts and so constitute seats for 55 the end portions of the splash cover and

gage 19. This splash cover is rectangular and substantially fills the space across the upper portion of the cup, and hence is securely held in place at a definite elevation by the kerfed shoulder portions 16 of the 60 binding posts. Said plate is provided with a central hole 20 through which the level of the electrolyte may be determined at any time.

The binding posts 11 and 12 are provided 65 with frusto-conical shoulders 21 and 22 respectively, each having at its lower end a horizontal flange 23, these features being adapted to support conical gaskets 24 of any suitable material. Above these shoulders 70 the binding posts are threaded at 25 for the accommodation of binding nuts 26 of any suitable but non-corrodible metal, or its equivalent, and above these threaded portions 25 of the binding posts the upper ends 75 thereof are tapered and preferably smooth and one of larger diameter than the other as plainly shown at 26' and 27.

The cover 28 is preferably of one piece 80 of any suitable material that will not be acted upon by the acids of the battery or otherwise deteriorate. The cover is provided with a reinforcement or stiffening flange 29 which is dropped down within the upper end of the cup and adapted to bear with a 85 fairly snug fit against the inner walls of the cup in practice just above the level of the electrolyte. The cover is furthermore provided with a plurality of longitudinal and transverse ribs 30 for reinforcement and 90 stiffening purposes. At the center of the cover I provide an internally threaded boss 31, the opening through which is directly above the hole 20. At about the center of each end of the cover I provide a downwardly projecting boss 32 having a hole constituting a counterpart of the frusto-conical shoulder and gasket 24 adapted to be projected thereinto with a snug fit. The cover is locked in the place indicated with respect 95 to the binding posts by means of the lock nuts 26 above described, the same bearing downward snugly against the top surface of the cover and serving to draw the cover downward with a snug liquid tight fit upon 100 the shoulders 21 and 22. After the parts are assembled in the manner just described and illustrated, the space between the downwardly projecting flange 29 of the cup is 105 filled with cement 33 of any suitable nature, 110

making a positive seal between the cover and the cup and leaving no openings or vents except through the threaded boss 31.

The vent plug 34 is constructed with a hollow body, the lower end of which is threaded at 35 for engagement in the threaded boss 31, the flange portion 36 of the plug thus coming down snug upon the upper end of the boss. The upper end of the body of the plug is provided with parallel fins 37 for easy manipulation of the plug. The upper and lower ends of the hollow body are guarded by diaphragms 38 and 39 respectively, the upper one having a central vent 38', while the lower one has a plurality of spaced vents 39' out of registry with one another and the hole 20 in the splash cover below. Any gases or fumes that may be generated within the cell have free exit through the vent holes through the plug, but because of the staggering relation of these features the cell as a whole is practically non-leakable. The main splash of the electrolyte within the cup is guarded by the splash cover 19, but any acid that may reach the bottom of the plug will pass through the vents 39' in very small quantities if at all, and if any of the acid should enter the plug by no possibility can it spurt or splash through the upper vent 38' and, furthermore, any acid that might enter the plug will be free to flow backward again through the vents 39'.

It will thus be seen that I produce a very

compact, strong, reliable and efficient battery cell because of the features of construction set forth herein.

I claim:

1. In a storage battery cell, the combination of a pair of binding posts having their intermediate portions enlarged and tapered, thin flexible gaskets encircling said enlarged portions, each post having at the lower edge of said enlarged portions an outwardly projecting flange to facilitate the placing of the gasket thereon and to assist in supporting the same, a cover plate resting upon the gaskets, and means carried by the posts serving to lock the cover thereon.

2. In a storage battery cell, the combination of a pair of spaced binding posts having sharp frusto-conical shoulders formed thereon intermediate their ends and at the same level, an outwardly projecting flange at the lower level of each shoulder, a thin conical gasket supported on said flange and embracing the shoulder, a cover having openings to receive said shoulders, the posts being screw threaded above the shoulders and having smooth tapered upper ends of reduced diameter, and binding nuts screwed upon the threaded portions of the binding posts in engagement with the cover and serving to make liquid-tight joints between the cover and the shoulders, said nuts being located below the smooth ends of the posts.

PAUL M. MARKO.
